CLAIM

The ornamental design for a coin depositing and dispensing apparatus, as shown and described.

DESCRIPTION

FIG. 1 is a perspective view of a coin depositing and dispensing apparatus showing our new design; FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom view thereof.

The broken lines in the drawings depict portions of the coin depositing and dispensing apparatus that form no part of the claimed design.

The different shading techniques used depict a contrast of appearance only and does not represent a particular color, material, or texture.
